UNITED STATES PATENT OFFICE.

THEODORE J. FREUND, OF CHICAGO, ILLINOIS.

PUNCH.

1,369,234.

Specification of Letters Patent. Patented Feb. 22, 1921.

Application filed January 12, 1920. Serial No. 350,740.

To all whom it may concern:

Be it known that I, THEODORE J. FREUND, a citizen of the United States, residing at Chicago, in the county of Cook and State of Illinois, have invented certain new and useful Improvements in Punches, of which the following is a specification.

This invention relates to improvements in punches.

10. One of the objects of the invention is to cheapen and simplify the construction of punches.

Another object is to provide a block within which a punch blade may readily be inserted and removed.

15. Another object is to provide a block in which a plurality of such blades, of various sizes, may be inserted, to be used alternatively or together.

20. Another object is to provide a punch block having a blade in the form of a broken ring of steel, sharpened on one of its longitudinal edges and possessing sufficient resiliency to retain it in place within the block.

25. Other, further and more specific objects of the invention will become readily apparent, to persons skilled in the art, from a consideration of the following description when taken in conjunction with the drawings, wherein:

Figure 1 is a side elevation of a punch press showing parts in sections and showing my improved punch therein.

Fig. 2 is a plan view of the punch block showing the punches inserted in the respective grooves.

Fig. 3 is a perspective view of one of the resilient broken rings forming a punch, adapted to be inserted in the block.

40. In all the views the same reference characters are employed to indicate similar parts.

5. is a punch press having a handle 6 for rotating the screw 7. A metal disk 8 is rotatably secured on the end of the screw 7, 45 as at 9, and secured to the underside of the disk 8 is a disk of relatively soft material 10, such as fiber, or the like. Mounted on the base 11 of the punch press is a separable punch block 12 having a series of concentric grooves 13, on one face, and a series of intermediate grooves 14 on the other face. A punch blade 15 consists of a spring ring, divided as at 16, and having a sharpened edge 17. The blade 15 is insertible in one 55 of the grooves, 13 or 14, on either side of the punch block 12. Blades 15, of different

sizes, are adapted for the grooves 13 and 14 so that disks of various diameters may be punched by the respective blades. Another blade 18, of smaller diameter, is shown 60 in the block 12 in one of the grooves 13, so that the material between the blades 15 and 18 will be in the shape of a ring, or washer. When the blade 18 is removed, the blade 15 will punch out a disk, but two blades, of different size may be used at the same time, as explained, so that washers may be punched.

The device is especially adaptable for punching disks, or rings from relatively soft 70 material, such as felt, leather, or the like. When the blades are put in the respective grooves, 13 or 14, they are of such length that the ends 16—16' will meet, thereby completing the ring and exerting sufficient frictional contact with the outer surface of the 75 groove to hold the ring in place.

In the use of the device, the goods to be punched are placed between the upper surface of the blades 15—18 and between the 80 blades and the relatively soft disk 10, whereupon the handle 6 is rotated which causes the screw 7 to move the disk 10 into substantial contact with the upper surface 17 of the ring 15, thus punching a round object, 85 disk, or ring from the material operated upon.

The punch block 12 shows nine separate grooves adapted for blades, 15—18, of various diameters so that practically any diameter of disk, or width of rings, may be punched within the ultimate capacity of the 90 blades.

By having the insertible blades in the punch block, considerable expense is saved 95 over the usual form of having a separate punch for each diameter of disk to be cut and by making the blades in the form of a broken ring, a blade may be produced from a strip of thin sheet resilient steel, thereby 100 greatly reducing the cost of the blades.

Having described my invention what I claim as new and desire to secure by Letters Patent, is:—

1. A punch block comprising a disk having a circular groove in one of its faces and a blade comprising a one piece split thin ring, having one of its longitudinal edges sharpened, and in frictional engagement with the inner surface of the groove by 110 which it is held in place.

2. A punch block comprising a disk hav-

ing a plurality of grooves in one of its faces and blades for insertion in the respective grooves, each blade comprising a one piece split ring held in the respective groove by 5 frictional engagement therewith.

3. A punch block comprising a disk having a plurality of grooves in each of its faces and a plurality of blades for insertion in the respective grooves, each blade 10 comprising a strip of steel formed into a one piece broken or split ring, and having one of its longitudinal edges sharpened.

4. A punch block disk having an annular groove in one of its flat faces; a one-piece split ring normally larger in diameter than the 15 groove and of length that its terminal ends meet when the ring is in contact with the outer annular vertical wall of the groove and held in place by frictional engagement with said wall of the groove.

20 In testimony whereof I hereunto subscribe my name.

THEODORE J. FREUND.
